UNITED STATES PATENT OFFICE.

EDWARD EARLE EVERETT, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA.

STORAGE-BATTERY GRID.

1,183,807.

Specification of Letters Patent. Pa
Application filed June 23, 1913. Serial No. 775,408

Patented May 16, 1916.

To all whom it may concern:

Be it known that I, EDWARD EARLE EVERETT, a citizen of the United States, residing at Philadelphia, in the State of Pennsylvania, have invented a certain new and useful Improvement in Storage-Battery Grids; whereof the following is a specification, reference being had to the accompanying drawing.

10 My improvement is particularly applicable to storage battery plates of the type known to the trade as "diamond" grids, because the openings to receive the active material, in the gratings forming the opposite plane faces thereof, are of the conventional rhombic diamond shape.

The process herein contemplated is described and claimed in my application Serial No. 842,689, filed June 3, 1914, for Letters Patent of the United States.

As hereinafter described my invention comprises a unitary metal casting including a rectangular plane frame having single members respectively forming the top and 25 opposite vertical edges of said plate, and having two parallel base bars at the bottom edge of said plate, each one-half the thickness of said plate; said frame having five partition bars, recessed in the direction of 30 their length between said base bars and extending parallel with said opposite vertical frame members, in spaced relation, forming between them a series of six vertical chambers in said casting, for active material, said chambers opening between said base bars and extending to the frame member at the top of said casting, said chambers being inclosed at the opposite plane faces of the casting by respective 40 gratings each formed of strips, in unitary relation with said casting, of outwardly converging V-shaped cross section, said strips intersecting in diagonal relation, with diamond shaped spaces between them; the 45 intersections of the strips in each grating being opposite the centers of the diamond-shaped spaces of the other grating; the strips intersecting intermediate of said partitions at the bottom thereof being separated from the adjacent base bar at said intersections and having auxiliary strips extending from the junctions of said base bar with said partitions in connection with 50 said intersecting strips between the inter-

sections thereof and said partitions. Said casting is molded around removable cores extending between said two base bars and occupying the respective chambers between said partition bars, and said base bars, being one-half the thickness of said plate, primarily project outward from the respective planes of the opposite foraminous faces of said plate, so as to afford a space between said base bars coextensive with the length thereof between the junctions of said base bars with said single frame members respectively forming the opposite vertical edges of said plate, to permit said cores to be removed. Thereupon, said base bars are pressed together, to close said chambers at the bottom thereof, and the active material, in the form of paste, or otherwise, is then manually, or otherwise, pressed into said chambers through the diamond-shaped openings of said gratings, or otherwise, by means of a pasting paddle, or other suitable means. The recesses in said partition bars between said base bars permit the latter to be pressed tightly together by the collapse of said recesses. The strips intersecting intermediate of said partitions at the bottom thereof are left separate from the adjacent base bar at said intersections so that when the bottom is pressed shut said strips will not be depressed to restrict the area of the chambers thereat, but remain flush with the opposite plane faces of the plate. If said intersecting strips were attached to the base bars, instead of being separate from the latter, they would be depressed inward not only restricting the area of the chambers immediately adjacent said base bars, but would afford no support for the active material immediately above said base bars, which material would have a tendency to fall out by the jarring movement to which such plates are subjected, particularly when used in motor vehicles. On the other hand, the pressure of the active material packed into the grid tends to force said bottom intersections of the strips outward when said intersections are thus left separate from the base bars and such tendency is overcome by the auxiliary strips aforesaid.

My invention includes the various novel features of construction and arrangement hereinafter more definitely specified.

In the drawings:—Figure I is a fragmen-

5 tary elevation of a storage battery grid embodying my improvement. Fig. II is a vertical sectional view of said grid, taken on the line II, II in Fig. I. Fig. III is an inverted plan view of the base edge of said grid as shown in Figs. I and II, *i. e.* with the base bars in the separated position in which they are primarily cast. Fig. IV is a fragmentary elevation of the right hand edge of said grid extending vertically in Fig. I. Fig. V is an inverted plan view, similar to Fig. III but showing the base bars pressed together to close the opening primarily existing between them. Fig. VI is a fragmentary sectional view, taken on the line VI, VI in Fig. V. Fig. VII is an inverted plan view similar to Fig. III but showing a modified form of my invention. Fig. VIII is a fragmentary elevation of the right hand edge of the grid shown in Fig. VII. Fig. IX is an inverted plan view similar to Fig. VII but showing the base bars pressed together to close the opening primarily existing between them. Fig. X is a fragmentary elevation, similar to Fig. VIII but showing said base bars pressed together as in Fig. IX. Fig. XI is a fragmentary elevation, similar to the lower left hand corner of Fig. I, but showing a modified form of gratings.

10 Referring to the form of my invention shown in Figs. I to VI inclusive; the plate 1 having the terminal lug 2 is a unitary metal casting including a rectangular plane frame having single members 4, 5 and 6 respectively forming the top and opposite vertical edges of said plate, and having two parallel base bars 7 at the bottom edge of said plate. As shown in Figs. III, V and VI each of said base bars 7 is one-half the thickness of said plate so that when pressed together as shown in Fig. V their opposite plane faces are flush with the opposite plane faces of said side frame members 5 and 6. In order to permit said base bars to thus close together they are tapered to less thickness at their junctions with said frame members 5 and 6 as shown in Figs. III and V. Said unitary metal casting includes the five partition bars 9 which are recessed, in the direction of their length, between said base bars 7 as indicated at 10, the upper ends of said recesses being wedge shaped as indicated in Fig. II. Said partition bars 9 extend parallel with said opposite vertical frame members 5 and 6, in spaced relation, forming between them a series of six vertical chambers 12 in said casting, for active material, said chambers opening between said base bars and extending to the frame members 4 at the top of said casting, as shown in Figs. II and III. Said chambers 12 are inclosed at the opposite plane faces of the plate 1 by respective gratings 14 and 15 each formed of strips 17

15 and 18 in unitary relation with said casting and of outwardly converging V-shaped cross section as shown in Fig. II. As shown in Fig. I said strips intersect in diagonal casted relation with diamond-shaped spaces between them; the intersections of the strips in each of said gratings 14 and 15 being opposite the centers of the diamond-shaped spaces of the other grating. As shown in Fig. I the strips 18 intersecting intermediate of said partition bars 9 at the bottom thereof are separate from the adjacent base bar 7 at said intersection and have auxiliary strips 20 extending from the junctions of said base bar 7 with said partitions 9 in connection with said intersecting strips 18 between the intersections of the latter and said partitions; said strips 20 being in unitary cast relation with said strips 18, base bar 7, partition bars 9 etc. As above noted such construction permits the base bar 7 to be compressed from the primary position, in which they are cast, as indicated in dotted lines in Fig. VI, to the final position, indicated in full lines in said figure, without depressing the adjacent intersecting strips 18 to restrict the area of the chambers 12, and leaving said intersections in position to support the active material without liability of being thrust outward by pressure of 95 said material, the latter tendency being overcome by said auxiliary strips 20. In this connection, it may be observed with reference to Fig. II that the strips 17 and 18 as they approach the base bars 7 are of slightly 100 greater thickness than at points remote from said base bar, and consequently the grid is to withstand the increased pressure of the active material which at the lower part of the finished electrode tends to outwardly 105 displace said strips.

10 Referring to the form of my invention shown in Figs. I to VI inclusive; the plate 1 having the terminal lug 2 is a unitary metal casting including a rectangular plane frame having single members 4, 5 and 6 respectively forming the top and opposite vertical edges of said plate, and having two parallel base bars 7 at the bottom edge of said plate. As shown in Figs. III, V and VI each of said base bars 7 is one-half the thickness of said plate so that when pressed together as shown in Fig. V their opposite plane faces are flush with the opposite plane faces of said side frame members 5 and 6. In order to permit said base bars to thus close together they are tapered to less thickness at their junctions with said frame members 5 and 6 as shown in Figs. III and V. Said unitary metal casting includes the five partition bars 9 which are recessed, in the direction of their length, between said base bars 7 as indicated at 10, the upper ends of said recesses being wedge shaped as indicated in Fig. II. Said partition bars 9 extend parallel with said opposite vertical frame members 5 and 6, in spaced relation, forming between them a series of six vertical chambers 12 in said casting, for active material, said chambers opening between said base bars and extending to the frame members 4 at the top of said casting, as shown in Figs. II and III. Said chambers 12 are inclosed at the opposite plane faces of the plate 1 by respective gratings 14 and 15 each formed of strips 17

15 and 18 in unitary relation with said casting and of outwardly converging V-shaped cross section as shown in Fig. II. As shown in Fig. I said strips intersect in diagonal casted relation with diamond-shaped spaces between them; the intersections of the strips in each of said gratings 14 and 15 being opposite the centers of the diamond-shaped spaces of the other grating. As shown in Fig. I the strips 18 intersecting intermediate of said partition bars 9 at the bottom thereof are separate from the adjacent base bar 7 at said intersection and have auxiliary strips 20 extending from the junctions of said base bar 7 with said partitions 9 in connection with said intersecting strips 18 between the intersections of the latter and said partitions; said strips 20 being in unitary cast relation with said strips 18, base bar 7, partition bars 9 etc. As above noted such construction permits the base bar 7 to be compressed from the primary position, in which they are cast, as indicated in dotted lines in Fig. VI, to the final position, indicated in full lines in said figure, without depressing the adjacent intersecting strips 18 to restrict the area of the chambers 12, and leaving said intersections in position to support the active material without liability of being thrust outward by pressure of 95 said material, the latter tendency being overcome by said auxiliary strips 20. In this connection, it may be observed with reference to Fig. II that the strips 17 and 18 as they approach the base bars 7 are of slightly 100 greater thickness than at points remote from said base bar, and consequently the grid is to withstand the increased pressure of the active material which at the lower part of the finished electrode tends to outwardly 105 displace said strips.

10 Referring to the form of my invention shown in Figs. I to VI inclusive; the plate 1 having the terminal lug 2 is a unitary metal casting including a rectangular plane frame having single members 4, 5 and 6 respectively forming the top and opposite vertical edges of said plate, and having two parallel base bars 7 at the bottom edge of said plate. As shown in Figs. III, V and VI each of said base bars 7 is one-half the thickness of said plate so that when pressed together as shown in Fig. V their opposite plane faces are flush with the opposite plane faces of said side frame members 5 and 6. In order to permit said base bars to thus close together they are tapered to less thickness at their junctions with said frame members 5 and 6 as shown in Figs. III and V. Said unitary metal casting includes the five partition bars 9 which are recessed, in the direction of their length, between said base bars 7 as indicated at 10, the upper ends of said recesses being wedge shaped as indicated in Fig. II. Said partition bars 9 extend parallel with said opposite vertical frame members 5 and 6, in spaced relation, forming between them a series of six vertical chambers 12 in said casting, for active material, said chambers opening between said base bars and extending to the frame members 4 at the top of said casting, as shown in Figs. II and III. Said chambers 12 are inclosed at the opposite plane faces of the plate 1 by respective gratings 14 and 15 each formed of strips 17

in Fig. XI, wherein the gratings at the respectively opposite faces of the plate 30 are respectively formed by strips 31 and 32 which extend from the frame members 33 to the vertical partition bars 34, and between the latter, without intersection. Said strips 31 and 32 are preferably so disposed as to afford diamond-shaped openings through the grid as shown in Fig. XI.

10 The base bars 36, shown in Fig. XI, may be constructed and arranged like the base bars 7, as shown in Figs. II to VI inclusive, or like the base bars 26 shown in Figs. VII to X inclusive. That is to say, said partition bars 34 are recessed in the direction of their length between said base bars 36 as indicated at 10 in Fig. II, but the frame bars 33 may be either thus recessed or not. Said grids are adapted to be supported by 20 resting upon two ribs, extending transversely to the planes, at the bottom of the battery cells, where I have made the base bars of greater vertical extent, as indicated at 40 in Fig. I and 41 in Fig. XI.

25 I find it preferable to make said castings of lead alloyed with antimony sufficient to impart the desired degree of rigidity.

I do not desire to limit myself to the precise details of construction and arrangement 30 herein set forth, as it is obvious that various modifications may be made therein without departing from the essential features of my invention as defined in the appended claims.

I claim:—

35 1. A storage battery grid consisting of a metal frame including two base members; and two parallel series of inclined strips of which certain strips adjacent the base members are structurally separate from and independent of said members.

2. A storage battery grid consisting of a metal frame including two base members; and two series of inclined intersecting strips of which certain strips adjacent the base 45 members are structurally separate from and independent of said members.

3. A storage battery grid consisting of a metal frame including two base members; partition members extending from said base 50 members; two series of inclined intersecting strips connecting the partition members of each adjacent pair thereof, certain of the intersecting strips adjacent the base members being structurally separate from and independent 55 of said members; with auxiliary strips extending from the junction of the base members with the partition members, to the adjacent intersecting strips.

4. A storage battery grid consisting of a 60 metal frame including two substantially parallel base members; partition members; and two series of strips connecting adjacent partition members, the lower ends of

the partition members being forked and the branches of each fork being respectively connected to the base members.

5. A storage battery grid consisting of a metal frame including two substantially parallel base members, each having a plurality of definitely placed vertically extended portions to strengthen it adjacent its points of engagement with the supporting ribs of a battery cell; partition members extending from said base members; and two series of strips connecting the partition 75 members.

6. A storage battery grid consisting of a metal frame including two substantially parallel base members; and two series of strips which increase in thickness as they approach said base members.

7. A storage battery grid consisting of a metal frame including opposite side members; with two substantially parallel base members of diminished thickness adjacent 85 their ends and having said ends connected to said side members.

8. A storage battery grid consisting of a metal frame including opposite side members; two parallel base members extending 90 between said side members; forked partition members extending from said base members; and two series of strips connecting the partition members of each adjacent pair thereof.

9. A storage battery grid consisting of a metal frame including opposite side members; two parallel base members extending between said side members; partition members extending from said base members; and two series of strips connecting the partition members; said base members being directly connected to each other at their ends only.

10. A storage battery grid consisting of a 105 metal frame including two substantially parallel base bars; and members having forked ends with their branches respectively connected to said base bars; with two series of strips connecting adjacent members. 110

11. A storage battery grid consisting of a metal frame including two substantially parallel base bars; and members having forked ends with their branches respectively connected to said base bars; with two series 115 of strips connecting adjacent members and made of increasing thickness as they approach the base bars.

In testimony whereof, I have hereunto signed my name at Philadelphia, Pennsylvania, this nineteenth day of June, 1913.

EDWARD EARLE EVERETT.
